(57) CLAIM

I claim the ornamental design for a face cleansing instrument, as shown and described.

DESCRIPTION

FIG. 1 is an upper perspective view of a front side of a face cleansing instrument in accordance with the present design; FIG. 2 is a lower perspective view of a rear side of the face cleansing instrument of FIG. 1;

FIG. 3 is a front plan view of the face cleansing instrument of FIG. 1;

FIG. 4 is a rear plan view of the face cleansing instrument of FIG. 1;

FIG. 5 is a left side plan view of the face cleansing instrument of FIG. 1;

FIG. 6 is a right side plan view of the face cleansing instrument of FIG. 1;

FIG. 7 is a top plan view of the face cleansing instrument of FIG. 1; and,

FIG. 8 is a bottom plan view of the face cleansing instrument of FIG. 1.

Directional terms (such as top, bottom, etc.) are made with regard to the face cleansing instrument as shown and positioned in the drawings and are not intended to limit the scope of the invention.

The broken lines shown in the drawings are for the purposes of illustrating portions of the article and form no part of the claimed design.
